The ornamental design for the mixing tool implement, as shown and described.

DESCRIPTION

FIG. 1 is a front view of a mixing tool implement, according to the new design;

FIG. 2 is a side view of the mixing tool implement of FIG. 1, the opposite side being identical thereto;

FIG. 3 is a rear view of the mixing tool implement of FIG. 1;

FIG. 4 is a bottom view of the mixing tool implement of FIG. 1;

FIG. 5 is top view of the mixing tool implement of FIG. 1;

FIG. 6 is first top perspective view of the mixing tool implement of FIG. 1;

FIG. 7 is second top perspective view of the mixing tool implement of FIG. 1;

FIG. 8 is first bottom perspective view of the mixing tool implement of FIG. 1; and,

FIG. 9 is second bottom perspective view of the mixing tool implement of FIG. 1.

The broken lines show portions of a mixing tool implement which form no part of the claimed design.
